An. 17.
George Reynolds, East Hartford, C't.

Letters Patent

The Schedule referred to in these Letters Patent and making part of the same containing a description in the words of the said George Reynolds, himself of his improvement in his feather dressing machine.

To all whom it may concern,

Be it known that George Reynolds of East Hartford in the County of Hartford and State of Connecticut have invented a new and useful improvement in his machine for dressing, cleaning feathers and preparing them for beds, and that the following is a full and exact description of the construction and operation of the said machine and also of the improvement so invented and improved by me. This machine consists of a cylinder or barrel of sheet copper or tin, three feet seven or eight in length and 18 inches or more in diameter as shall best suit the operator. On one side of the cylinder is a door which for convenience should be nearly the whole length of the cylinder and of sufficient width for putting in and emptying out the feathers. Through the centre of this cylinder it is made to induce a shaft of wood or metal into which are inserted pins called dressing pins of large wire or any other material that may be thought suitable, the number and length of which may be varied according to the length and diameter of the cylinder and the judgment of the operator. In the centre of each end or head of the cylinder is a hole through which a key may be turned into the end of the shaft. One of these keys, from the first of the crank for turning the cylinder has a nail or bolt outside of the head of the cylinder which is forced up so as to confine the head of the cylinder and end of the shaft so that both may turn together. The key may be turned out and the shaft taken out at pleasure. Upon the neck of one of these keys, it may be at either end, the cylinder is a tooth wheel so made that the key may revolve within the center hole of the wheel without turning the wheel. Between the center shaft and the outside of the cylinder are one, two or more

auxiliary shafts each carrying a set of dressing pins so placed as to play between them in the center shaft. These shafts turn upon guides also passing through the heads of the cylinder. On the guides of these shafts at the end where the toothed wheel is placed on the center shaft guides are fixed corresponding toothed wheels playing into the center one so that when the cylinder is made to revolve on the main shaft the auxiliary shafts revolve in the opposite direction the center wheel being in this case prevented from revolving by means of two short arms, fastened to the spoke of the wheel and resting on the same bar which supports the machine and on which the guides of the main shaft rest. The head of the cylinder near the nozzle is not fastened to the body of the cylinder but made with a narrow rim similar to the cover of a teapot box and sets close either within or over the body of the cylinder and can be taken off when necessary to take out the shaft. Both heads may be made in the same manner if preferred. On the ends of heads of the cylinder are several small holes for letting out air and steam, and in the door of the cylinder are several small holes for letting out carbon of coke may be among the feathers. To use this machine if in a room with a fire place a sort of stove suited to the size of the machine may be built of brick on the hearth filling up the fire place except an opening at top to take off the smoke after this a small fire is kindled over which the machine is hung by the guides resting on brick feet so as to turn upon. & soon the whole may be placed a cover of sheet iron is then to cover the heat around the cylinder and turn the machine into the opening left for it. or as at stove or furnace of brick or sheet iron may be made in which to suspend the cylinder some what similar to a fire oven at Franklin stove with a flue or pipe at top to carry off the smoke or gas from the fire of wood or coal. If made of sheet iron the whole will be considerably lighter. The form of construction is somewhat provided the heat is communicated properly to the cylinder. The feathers to be scraped if very foul and badly matted will require washing and action about half a day are

are introduced in order for drying but this is seldom necessary, in most cases they need only to be introduced according to the condition they are in, sufficient quantity to operate upon and into the machine and the machine placed over the fire. When the cylinder is turned slowly around till the feathers are entirely dry which may be known from the same ceasing to issue from the holes in the body of the cylinder. The feathers are caused round with the cylinder till they come to the top when while act they fall. This going in the several shafts at the same time separating and working them together and by constantly changing their position give them an equal chance to the heat and however dried and rolled before they come from the machine as light and lively as new feathers. If the feathers have contained any quantity of the solution of 60 grains of lime sprinkled on them before the operation will entirely destroy it. When one batch is full it is time the machine is taken from the fire and placed on a stand, or support for the purpose of a light flame on which the machine may rest permanently and be placed over and away from the fire all together, may be preferred when by opening the door and turning it down the feathers are emptied out. Then turning the door up again the cylinder is filled and placed over the fire for another operation. By this process every dangerous odor either in old or new feathers is entirely removed, every feather this process is very useful by destroying the natural root, to which adheres to them and thus fitting them properly for new body. I do not claim as my invention the cylinder, the shafts, the fire - nor indeed any several parts of the machine taken by itself but of claiming any invention the combination of the several parts of the machine as above described and applicable to the particular object aforesaid and the manner of communicating the heat to the feathers by means of the rotation of the cylinder preventing every article the fire in rotation and communicating the heat to every part of the feathers as they are kept in contact.

linal motion by the driving pin. The working of the cylinders and the auxiliary shaft and also the tube to burn or be overheated. The foregoing specification is copied from a former one to which Letters Patent were granted me dated Oct 17 1885, excepting only such alterations and additions as necessary on account of the improvement in the machine which I am desirous of securing. This may be judged according in order to explain more clearly the improvement as connected with the machine in its construction and operation as appears by the drawings making a part of the specification and the references therein contained. The improvement in this further driving machine which I claim as my invention other than what is already granted consists in the addition and combination of the auxiliary shafts or shafts with their pins and the toothed wheels gearing into each other in the manner herein described as to carry the auxiliary shafts around the main shaft while at the same time they revolve on their own axes.
